CLAIM

The ornamental design for a stethoscope chestpiece, as shown and described.

DESCRIPTION

FIG. 1 is a perspective view of a stethoscope chestpiece; FIG. 2 is a front view thereof;

FIG. 3 is a top view thereof;

FIG. 4 is a left side view thereof, a right side view being a mirror image thereof;

FIG. 5 is a bottom view thereof; and,

FIG. 6 is a rear view thereof.

The portions of the stethoscope chestpiece in FIGS. 1-6 shown in broken lines are included to show features that form no part of the claimed design.

1 Claim, 3 Drawing Sheets
